MINE MOORING CUTTER

Edward C. Craig, United States Navy

Application April 30, 1941, Serial No. 391,174

1 Claim. (Cl. 114—221)

(Granted under the act of March 3, 1883, as amended April 30, 1928; 370 O. G. 757)

This invention relates to a mine mooring cutter, and has for an object to provide an improved device for mechanically cutting moorings, cables or anchor chains of submarine mines.

A further object of this invention is to provide a mine mooring cutter which utilizes the tension in the sweep cable to complete a cutting operation initiated by the mine mooring contacting with the serrated V-shaped knife.

Still a further object of this invention is to provide a mine mooring cutter having a serrated knife for initiating the cutting action of the mooring and having a pivoted knife connected to the cable and released for pivotal action by a trigger contacted by the mine mooring to pivot this knife and complete the cutting operation.

Still a further object of this invention is to provide a combination of a shear knife and a pivotal knife in a mine mooring cutter which cooperate to cut a mine mooring, and then after the cutting is completed serve to by-pass a subsequent mine mooring to a further cutting device located in the sweep cable.

With the foregoing and other objects in view, the invention consists in the construction, combination and arrangement of parts hereinafter described and illustrated in the drawing, in which:

Fig. 1 is an elevational view of the mine mooring cutter of this invention;

Fig. 2 is an edge view of the cutter of Fig. 1;

Fig. 3 is a plan view of the pivoted knife releasing trigger; and

Fig. 4 is a plan view of the pivoted knife.

There is shown at 10 the mine mooring cutter of this invention, comprising a body 9, secured within the mine sweep cable 12 by rotatable joints 13 and 14, thereby enabling an extending fin 11 to easily rotate the body 9 to a horizontal position as the cutter 10 is pulled through the water by the sweep cable 12 in the direction of the arrow 15. The rearward joint 13 is secured to the body 9 by a pivoted link 16, while the forward joint 14 has a link 17 pivotally securing it as at 18 to an arm 20, which, in turn, is pivoted at 21 to the body 9. The body 9 is provided at 22 with a serrated V-knife, one of whose edges 23 lines up with the forward edge 24 of the body 9.

This forward edge 24 in turn is substantially in alignment with the forward portion of sweep cable 12 so that as the cutter is drawn through the water between a pair of mine sweepers a mine mooring or anchor cable 25, struck by the sweep cable 12, will travel along the forward sweep cable 12 over the forward leading edge 24 of body 55

9, along the jaw 23 and into the serrated V-knife 22 to be at least partially severed thereby. Extending across the open jaw 23 is a trigger 26 pivoted at 27 to one side of body 9. A hooked finger 28 on trigger 26 is provided with a boss 30, extending at right angles to the plane of the trigger 26 through a suitable opening 31 in the body 9 to the opposite side thereof.

On this opposite side, that is, the upper side, as in Fig. 1, there is mounted a knife 32, pivoted to the body 9, as at 33. This pivoted knife 32 is provided with a notch 34 into which the boss 30 of trigger 26 extends, preventing this knife from pivoting in a counter-clockwise direction, as shown by arrow 35. This knife 32 is generally circular except for a sector cut away, and in this sector edge there is provided a U-shaped knife edge 36 whose medial radial distance from the knife pivot 33 is substantially equal to the distance between the pivot 33 and the center of the serrated V-knife 22. Secured to the pivoted knife 32 adjacent the end of the notch 34 is a flexible metallic strap 37 which is anchored thereto as by a rivet 38, while its opposite end is secured by a bracket 40 to the end of arm 20 adjacent pivot 18.

In operation, as the mine mooring 25 enters the serrated V-knife 22 it simultaneously strikes the hooked end 41 of the trigger 26, causing the trigger 26 to shear through the shear pin 42 extending through suitably aligned holes in the trigger 26 and body 9. As the shear pin 42 is cut through the trigger 26 yields under pressure of the mine mooring to withdraw the boss 30 in the notch 34, causing it to release the knife 32. With the pivoted knife thus released, the tension in the forward sweep 12 pulls arm 20 to the position 20' about its pivot 21, and simultaneously pulls the flexible strap 37 to the position 37', thus pivoting the knife 32 about 90°, bringing the cutter edge 36 to the position 36' at the inner end of the serrated V-knife 22.

As it travels through this position it does so in a very quick motion and under the tension of the towing sweep cable 12. The knife edge 36 will thus shear through the mine mooring 25 which has been at least partly sheared by the serrated edges of the V-knife 22. The cutting of the mine mooring 25 is thus assured. Then, the circular edge 43 of the rotatable knife 32 guards against a subsequent mine mooring entering the V-knife 22 and insures instead that it will travel there-over past the following sweep cable 12 to a subsequent similar cutting device, where it will be positively severed in a like manner.

Other modifications and changes in the num-

ber and arrangement of the parts may be made by those skilled in the art without departing from the nature of this invention, within the scope of what is hereinafter claimed.

The invention described herein may be manufactured and used by or for the Government of the United States of America for governmental purposes without the payment of any royalties thereon or therefor.

Having thus set forth and disclosed the nature of this invention, what is claimed is:

A mine mooring cutter comprising a fin body, a pair of sweep cable members secured to opposite sides of said fin body, one of said cable sweep members being directly secured to said fin body, 15 said cable member being a following cable member, a link pivoted to said fin body, the other of said sweep cable members being secured to the end of said link, said latter cable member being the fin body towing cable member, a pair of shear blades, one of said blades being secured on said fin body, a rotatable knife body pivoted on said fin body, the other of said blades being secured 20 on said rotatable knife body, said rotatably

mounted blade being adapted to sweep over said blade secured on said fin body, a tension member secured at one end to the cable securing end of said link, the other end of said tension member being secured to the periphery of said rotatable knife body in a position tending to rotate said knife blade body, a bell crank trigger member pivoted centrally of its ends on said fin body, one end of said trigger member extending across said fixed blade, a boss on the other end of said bell crank trigger member extending into a recess in said rotatable knife blade body, whereby when a mine mooring traveling along said link connected sweep cable towing member abuts said fixed knife blade, it pivots said trigger member to withdraw said trigger boss from said recess in said knife blade body, freeing it for rotation by said tension member secured to said link connected sweep cable towing member and causing said rotatable knife member to cut the mooring cable against said fixed knife blade, said towing cable member serving to rotate said rotatable knife member over said fixed blade.

EDWARD C. CRAIG.
